COIN OPERATED LOCKING RACK FOR SKIS

Emil J. Braun, Minneapolis, Minn., assignor to Valv-O-Matic, Inc., Minneapolis, Minn., a corporation of Minnesota

Filed Apr. 14, 1966, Ser. No. 1,892

Term of patent 14 years

(Cl. D80—10)

FIG 1

FIG 2

FIG 3

FIG4

FIGURE 1 is a front elevational view of a coin operated locking rack for skis showing my new design;

FIGURE 2 is a top plan view thereof;

FIGURE 3 is a bottom plan view thereof; and

FIGURE 4 is a side elevational view thereof.

I claim:

The ornamental design for a coin operated locking rack for skis, substantially as shown.
